Primary Examiner—M. N. Pandozzi*Attorney, Agent, or Firm*—Roberts & Brownell, LLC[57] **CLAIM**

The ornamental design for a cup, as shown.

DESCRIPTION

FIG. 1 is a front, elevational view of a cup showing my new design;

FIG. 2 is a top plan view thereof;

FIG. 3 is a bottom plan view thereof;

FIG. 4 is a left side elevational view thereof;

FIG. 5 is a rear elevational view thereof;

FIG. 6 is a right side elevational view thereof; and,

FIG. 7 is a flat elevational view of the label portion of the cup, with the cup portion removed for ease of illustration.
